UNITED STATES PATENT OFFICE.

ABRAHAM S. PIATT, OF WEST LIBERTY, AND ELMER E. WOLF, OF SPRINGFIELD, OHIO; SAID WOLF ASSIGNOR TO SAID PIATT.

ROTARY STEAM-ENGINE.

SPECIFICATION forming part of Letters Patent No. 633,730, dated September 26, 1899.

Application filed December 10, 1898. Serial No. 698,817. (No model.)

To all whom it may concern:

Be it known that we, ABRAHAM S. PIATT, residing at West Liberty, in the county of Logan, and ELMER E. WOLF, residing at Springfield, in the county of Clark, State of Ohio, citizens of the United States, have invented certain new and useful Improvements in Rotary Steam-Engines, of which the following is a specification, reference being had thereto in the accompanying drawings.

This invention relates to certain new and useful improvements in steam rotary engines.

The objects of our invention are, first, to arrange a pair of pistons within a suitable casing with a steam-feed conduit between them, the steam in which conduit may be automatically directed alternately against each piston and will act on them expansively during a sufficient length of time to utilize the full force of the steam; second, to provide mechanism whereby the steam will be admitted to each cylinder casing or chamber on opposite sides of the same piston at the same time; third, to provide suitable reversing mechanism which will cause the steam to be so directed against each piston as to reverse their direction of rotation, and, fourth, to provide partially-rotatable abutments which are adapted to be so rotated through the reversing mechanism and held in such position by steam-pressure and which are also capable of such rotation by the direct connection with the pistons themselves.

Our invention also relates to details of construction and arrangement hereinafter appearing, and particularly pointed out in the claims.

In the accompanying drawings, on which like reference letters and figures indicate corresponding parts, Figure 1 is an end elevation, partly in section, the section being taken on the line $y-y$ of Fig. 2; Fig. 2, a longitudinal sectional view taken on the line $x-x$ of Fig. 1; Fig. 3, a detail perspective view of one of the bushings on which the engine is mounted; Fig. 4, a sectional view on the line $z-z$ of Fig. 2 looking in the direction of the arrow; Fig. 5, a partial plan and sectional view, the section being taken on the line $z'-z'$ of Fig. 4; and Fig. 6, a similar view to Fig. 1 with the end plate removed and showing the relative posi-

tions of the deflector-valves and pistons to each other.

The letter A represents a suitable shell or casing to which are secured end plates B by means of lag-screws C or in any other suitable manner. This shell or casing and its end plates are carried by supports or legs D. The interior of the casing is divided into two main parts E and F, respectively, within which are fitted rotatable pistons G G'. Between these pistons is located a dividing member H, within which are located inlet-passages I I and exhaust-passages J. The inlet-passages communicate with an inlet-port K, while the outlet-passages communicate with an exhaust-port L. Within each inlet-passage is located a cut-off valve M, having a valve-stem N. This valve is so formed that at one time it may direct the steam from the passage I into a steam-chest O, formed by an extension of the casing within each of the piston-chambers, it being understood that there is one steam-chest for each piston at each end of the engine, as will presently appear. Within each of these steam-chests is located a partially-rotatable deflector P, which is mounted on a shaft Q. The shaft Q carries a key R, projecting within a space S in the hub of the deflector. This space S permits the deflector to be partially rotated on the shaft without any movement of the shaft, such construction permitting the steam-deflector to be thrown to the dotted position, as shown in Fig. 1, by means of the rotatable piston G', as it has a somewhat cam-like outline. In order to prevent the escape of steam past the deflector, we provide an extension T therefrom, against which the steam acts to hold the extension in close contact with the rotatable piston. To prevent undue wear on the extension, we have provided a rubbing-surface U, preferably formed of steel or other suitable material, as clearly shown in Fig. 1. A passage is formed in the steam-chest between the deflector and the cylinder-casing, as shown at V. Thus as the steam enters through the inlet-passage I it will pass between the deflector and casing and abut against the rotatable piston G' in its piston-chamber. In order to prevent the steam from passing through the passage W between the

deflector and the casing, we provide a partially-rotatable abutment X, which makes tight contact with said deflector. This abutment is provided with a packing Y and a lug 5 Z. The packing Y assists in making the joint between the deflector and abutment perfectly tight, and the lug Z is engaged for the purpose of causing the abutment to partially rotate, as will shortly appear. It will be seen 10 that such abutment acts as a stationary stop against which the steam may act in one direction, and consequently the force of the steam is directed against the piston to rotate it. When such deflector is moved from the 15 full-line position to its dotted position by means of the piston, the abutment X will remain in contact therewith; but when the deflector is operated by means of reversing mechanism, which will be hereinafter de- 20 scribed, the lug a is brought into engagement with the abutment X and causes it to partially rotate, and the lug b will engage with a projection c, extending from the second abutment d, and will partially rotate such abutment, 25 so that its end e will engage with the deflector and the packing f will make a perfectly tight joint, whereby there will be no leakage of steam between said second abutment and deflector. Thus the steam will flow through 30 the passage W against the rotatable piston at one side of its center. This will cause the piston to rotate in one direction, while when the deflector is so arranged that the steam will travel through the passage V the piston 35 will be acted upon at the other side of its center and will travel in the opposite direction.

We have thus seen how the steam enters into one steam-chest and from there how it 40 acts on the piston to rotate it in either direction.

We will now refer to the manner in which the steam is directed against the piston G. By referring again to Fig. 5 it will be ob- 45 served that when the valve M is turned to the full-line position the steam will flow into the adjacent steam-chest O, which is provided with a similar deflector and abutments, as above described. From this steam-chest it 50 passes into contact with the piston G.

We have now described the manner in which the steam is conducted first into one steam-chest and then into another steam-chest at one end of the engine; but it will be under- 55 stood that the opposite end of the engine is similarly constructed, and consequently a description of the working parts for one will answer for both. We will therefore now pass to a description of the mechanism for oper- 60 ating the cut-off-valve stem N and its valve, whereby the steam is conducted first against one piston and then against the other. By referring to Figs. 1 and 2 it will be seen that on each side of the inlet-port K we have pro- 65 vided a cylinder g. Within each of these cylinders is mounted a piston h on a piston-rod i in any suitable manner, such as be-

ing screwed thereon. The piston-rod passes through cylinder-heads j and glands k. In order to make the joint tight between the piston-rod and the heads, packing l is provided, which surrounds the piston-rod and is located between the head, as clearly shown in Fig. 1. To each end of this piston-rod is secured a bifurcated head m, while on the upper end of each of the valve-stems N is secured a cross-head n. To each end of these cross-heads is pivoted one end of a bar o and p, respectively, which at their other ends project within their respective bifurcated heads m, as above de- 70 scribed. By referring to Fig. 1 it will be seen that each piston-compartment communicates with the cylinder g, near each end, on each side of the piston h. When the deflector P and one of the pistons are in the position indicated in Fig. 1, the steam will pass through the passage q and into the cylinder g, which will cause the piston h to assume the position illustrated in Fig. 1 and at the same time will rock the cross-head n, and thereby rotate the 75 cut-off M from the dotted position to the full-line position, as clearly indicated in Fig. 5, which will direct the steam into the adjacent steam-chest to operate on the other piston. While this is being accomplished the piston G' is being acted upon by the expansion of the steam until the point r of the piston is advanced to close the passage V between the deflector P and the casing. At such time the steam in the cylinder g will be forced through 80 the passage q into the space between the piston G' and its casing by means of the live steam acting against the piston F in the cylinder g on the opposite side of the inlet-port K. As soon as the point s of the piston G' 85 travels past the point t of the casing, as shown in Fig. 6, the spent steam passes into one branch J of the outlet-passage, as shown in Fig. 4, which communicates with the exhaust-port L above described. A corresponding 90 outlet-opening J is shown back of the deflector P in the sectional part of Fig. 1, the deflector in the opposite end of the engine occupying 95 the same relative position. From Fig. 6 it will be seen that the steam is let into the piston inclosure at such points that it strikes the piston at opposite sides, and consequently 100 it remains in a balanced condition, which increases the wearing qualities of the engine and also tends to reduce the friction in the 105 bearings.

In order to prevent the live steam from blowing out through the exhaust-ports before acting on the piston, it will be understood that when the point r on the piston reaches the point v of the casing, and thereby cuts off the steam, the point s of the piston will not have passed by the point t in the casing. The same is true as to the points r' and s' on the opposite side of the piston with respect to the points v' and t' in the casing. 115

Referring now particularly to Fig. 1, the relation of the cylinders and corresponding deflectors maintain to each other will be clearly 120

seen—that is, when the steam is acting against one piston and the passage *q* is open the steam is cut off from the other piston and the corresponding passage *q* is closed by its piston.

5 We will now refer to the mechanism for reversing the rotation of the pistons. This consists of a lever 2, (shown in dotted lines in Fig. 1,) which is secured to one of the shafts *Q* for the purpose of partially rotating said 10 shaft and through it the deflectors in the steam-chests in one end of the engine. To this lever is attached one end of a connecting-bar 3, which at its other end is attached to a short crank-arm 4, clamped to the deflector-shaft 5, as shown at 6, and also keyed thereto, as shown at 7. As the shafts *Q* are rotated the keys *R* engage with one or the other of the shoulders 8 in the hubs of the deflectors and partially rotate such deflectors 15 for the purpose heretofore described. When they are so rotated that the steam in the steam-chests passes through the passages *W*, the passage *g*, leading into the cylinder *q* at one side of the piston *h*, will conduct the 20 steam into the cylinder *g* in a similar manner and for the same purpose as the passage *q* above described.

In order to limit the movement of the reversing mechanism, we provide an adjustable 30 stop 10, as shown in Fig. 1.

We will now refer to the manner of packing the pistons so that no steam will escape between their ends and the central partition and end plates. As illustrated in Fig. 6, a 35 circular groove 11 is cut in each end of the pistons, and in this groove is placed a ring 12. This ring is held in close contact with the respective end plates and central partition by means of springs 13, arranged at intervals within holes 14 and adapted to press 40 on arms 15, pivoted at one end of a cross-bar 16, forming a packing extending across the piston and projecting behind said rings. Springs 17 also act to keep the cores or packing-bars 16 in engagement with the casing 45 during a portion of the rotation of said piston at least. Thus steam is effectually prevented from escaping except at the proper time, when it passes through the exhaust-port designed 50 for it, as above described.

In order to maintain a true relation between the casing and pistons, we provide conical-shaped bearings 18, 19, and 20. These conical bearings have a number of slots in them, 55 as shown at 21 in Fig. 3. These slots are so arranged that one of them opens from one end while the next one opens from the other end and alternate in this manner around the bearing. This is for the purpose of permitting the bearing to yield more or less. From one end of the bearing extend lugs 22, which are provided with holes 23 for the reception 60 of screws 24. These screws are adapted to screw into the casing to any desired amount. 65 Their outer end is also screw-threaded, and the nut 25 is adapted to screw against the bearing and move it longitudinally against a

shoulder 26 on the screw, as clearly shown in Fig. 2. Thus all wear is provided for and both cylinder and casing will maintain their 70 true relation to each other at all times. Oil-holes 27 are provided for oiling the shaft in the outer bearings.

In order to let out condensed steam from the piston-chambers, we provide petcocks 29, 75 which extend through each of the end plates and communicate with the interior of the piston-chambers.

Having thus fully described our invention, what we claim as new, and desire to secure by 80 Letters Patent, is—

1. In a rotary steam-engine, the combination with a shell or casing having a pair of chambers located therein, a driving-shaft extending through said casing and having a pair 85 of pistons rigidly mounted thereon within their respective chambers, of a partition having a steam inlet and exhaust passage located therein, a cut-off located in said inlet-passage, means to partially rotate said cut-off automatically to direct the steam alternately against said pistons during each revolution of the driving-shaft, steam-chests between said inlet-passage and said pistons, a deflector located within each of said chests and adapted 90 to direct the steam against said pistons at either side of said driving-shaft according to which direction the pistons are desired to rotate, substantially as shown and described.

2. In a rotary steam-engine, the combination with a shell or casing having a pair of chambers located therein, a driving-shaft extending through said shell or casing and having a pair of pistons rigidly mounted thereon within said respective chambers, of a steam-chest 105 for each piston having a deflector located therein, with a passage between said deflector and the walls of said steam-chest for the passage of steam into the piston-chamber, an abutment against which the steam may 110 react to drive the piston, a steam-passage leading into said steam-chests and having a valve located therein adapted to direct the steam first into one steam-chest and then into the other steam-chest during each complete 115 rotation of the driving-shaft.

3. In a rotary steam-engine, the combination with a shell or casing having chambers located therein, a driving-shaft extending through said casing and having pistons rigidly mounted thereon within said chambers, of steam-chests forming extensions from said chambers each having a steam-deflector located therein, means for partially rotating said steam-deflectors to cause them to direct 120 the steam above and below the center of said pistons according to the direction the pistons are rotating, a pair of abutments in each steam-chest one of which is adapted to be in close contact with one of said steam-deflectors 125 when the steam is being directed above said shaft, and the other of which is adapted to be in close contact with said deflector when the steam is directed against the piston below its 130

- shaft, a means, constituting a steam-inlet passage leading into the steam-chests, and a cut-off in said passage adapted to automatically direct the steam first into one chest and then 5 into the other alternately during each revolution of the pistons, substantially as shown and described.
4. In a rotary steam-engine, the combination with a shell or casing having chambers 10 located therein, a driving-shaft extending through said casing and having pistons rigidly mounted thereon within said chambers, of a partition between said pistons having a pair of inlet and a pair of outlet passages 15 therein, a cut-off within each of said inlet-passages, a pair of steam-chests connected with each of said inlet-passages, a deflector mounted in each of said chests adapted to contact with the respective pistons, as also a 20 pair of abutments adapted to contact with each of said deflectors, means for partially rotating said deflectors, and through them said abutments alternately into and out of contact therewith, means to partially rotate each 25 of said cut-offs in said inlet-passages to alternately deflect the steam into the adjacent steam-chests during each revolution of the piston, substantially as shown and described.
5. In a rotary steam-engine, the combination with a shell or casing having a pair of piston-chambers located therein as also a pair 30 of steam-chests in each end of said casing communicating with said piston-chambers, a pair of pistons for each of said piston-chambers rigidly mounted on a driving-shaft extending through said casing, of a partition between said pistons, a pair of inlet-passages and 35 a pair of outlet-passages therein, said inlet-passages communicating with their respective steam-chests and said outlet-passages communicating with said piston-chambers, a cut-off in each of said inlet-passages, said cut-off having a stem extending therefrom, a pair of cylinders secured to said casing and communicating with the respective piston-chambers, a piston mounted on a suitable piston-rod within each of said cylinders, means for 40 connecting each end of said piston-rod with the respective stems, whereby said stems are 45 partially rotated as also their cut-offs through steam-pressure and the steam is deflected first into one set of steam-chests and then into the other set of steam-chests alternately during 50 each revolution of said pistons, substantially 55 as shown and described.
6. In a rotary steam-engine, the combination with a shell or casing having a piston mounted therein on a driving-shaft and adapted 60 to rotate said shaft, a steam-chest also located within said casing, a shaft extending through said steam-chest, and having a deflector mounted thereon, said deflector being adapted to partially rotate independent of 65 said shaft by said piston and also adapted to be partially rotated by said shaft to deflect

the entering steam above and below the center of said piston according to the direction of rotation desired, substantially as shown and described.

7. In a rotary steam-engine, the combination with a shell or casing having a piston mounted therein on a driving-shaft and adapted to rotate said shaft, a steam-chest communicating with the interior of said chamber, a deflector-shaft extending through said steam-chest and having a deflector mounted thereon and adapted to be partially rotated by said piston and also partially rotated by its shaft, of a pair of abutments pivoted within said steam-chest and adapted to alternately contact with said deflector, according to the position to which the deflector has been operated through its shaft, substantially as shown and described.

8. In a rotary steam-engine, the combination with a shell or casing having a piston mounted therein on a driving-shaft and adapted to rotate said shaft, of a steam-chest communicating with the interior of said shell or casing, a shaft extending through said steam-chest having a deflector mounted thereon and within said chest, said deflector being adapted to be partially rotated by said shaft and by said piston, a pair of abutments pivoted within said steam-chest and adapted to contact therewith, a lug or projection extending from each of said abutments, a projection for each abutment carried by said deflector and adapted to engage with said abutment projections whereby when the deflector is partially rotated through its shaft one of said abutments will be thrown out of contact with the deflector and the other abutment will be thrown into contact with said deflector, thereby directing the steam either side of the center of 105 said piston, substantially as shown and described.

9. In a rotary steam-engine, the combination with a shell or casing having a pair of chambers located therein, a piston for each 110 of said chambers mounted on a shaft, of a partition having a steam-inlet passage located therein, a cut-off in said inlet-passage, means to partially rotate said cut-off automatically to direct the steam alternately against 115 said pistons during every half-revolution of the driving-shaft, steam-chests between said inlet-passage and said pistons, a deflector located within each of said chests and adapted to direct the steam against said pistons at 120 either side of said driving-shaft, according to which direction the pistons are desired to rotate, substantially as shown and described.

In testimony whereof we affix our signatures in presence of two witnesses.
